IGNITION TIMING GOVERNOR AND
DISTRIBUTOR

Marion Mallory, Detroit, Mich., assignor to Mallory Research Company, Toledo, Ohio, a corporation of Delaware

Application May 26, 1934, Serial No. 727,758

10 Claims. (Cl. 200—31)

One object of this invention is to improve the timing of the ignition on an internal combustion engine by modifying the action of a centrifugal governor by means of the friction developed in the distributor so that the centrifugal force is opposed at first only by this friction, which results in an initial advance which is at a greater rate per R. P. M. than is the subsequent rate.

Another object is to apply additional or alternative friction to accomplish the same result. A spring load is subsequently applied in the well-known manner to assist the friction in opposing the centrifugal force.

The governor characteristics desired show a rapid advance at the lower engine speed and a much slower advance at the higher engine speed.

Fig. 1 shows a perspective elevation view of the complete device except for the circuit breaker.

Fig. 2 shows a particular plan view on plane 2—2 of Fig. 1.

Fig. 3 is a plan view on the plane 3—3 of Fig. 1. Fig. 4 is a plan view on the plane 4—4 of Fig. 1.

In the figures:

10 is the driving shaft, having a serrated portion 11, which engages with the disc 12 to which is connected the plate 13. A second plate 14 and a third plate 23 are freely mounted on the shaft 10. They are free to move past the pins 34 and 35, which pins support the cam 33, having the two cam surfaces 31 and 32. The plate 23 is rigidly connected to the hollow shaft 24, which carries the timer cam 43 and also the distributor arm 45, which is made of a hard insulating material such as bakelite. Pins 17 and 18 project from the plate 13. These pins 17 and 18 are connected with pins 15 and 20 on the plate 14 by means of the radial springs 16 and 19. Centrifugal weights 27 and 28 are shown pivotedly mounted on the pins 26 and 29 which project from the plate 23 and these centrifugal weights have projections 25 and 30, which engage with the cam surfaces 31 and 32.

A friction device 36 is shown in Figs. 1 and 2 engaging with the hollow shaft 24. 36 is preferably a piece of leather. The friction is applied by means of a plunger 37 and the spring 38.

The plunger 37 moves in the cylinder 40, and the stop 41 is used to apply a definite pressure to the spring 38. 41 is threaded at 39 into the governor housing 42. A distributor housing 44 of hard insulating material is concentrically mounted above the governor housing 42. In the distributor housing 44, having a cover 51 integral

therewith, a distributor terminal 49 is mounted, which is one of a number.

In order that the conductor 47 shall engage with the terminal 48 and also with the terminal 49, it is made in the form of a compound spring. This form of distributor imposes a certain amount of friction determined by the resiliency of the member 47. 47 is anchored to the distributor arm 45 by means of a set screw 46.

The characteristic feature of the governor resides in the two plates 23 and 14. 23 is fixed to the hollow shaft 24. The plate 14 is free except for the fact that the pin 15 has only a limited movement in the slot 21 of the plate 23. In a similar way, the pin 20 has a limited movement 15 in the slot 22. These two pins 15 and 20 are diametrically opposite to each other.

Fig. 4 shows the circuit breaker mechanism comprising cam 43, which engages with a pair of rocker arms 58—59, which rock around pivots 60—61. Flat springs 62—63 apply the necessary pressure so that the rocker arms follow the movement of the cam 43 even at 2000 R. P. M. The springs are anchored at 67 and 68 to the circuit breaker plate 70. This plate 70 is mounted rigidly 25 in the governor housing 42, so that the cam 43 constitutes the sole means for timing the ignition contacts 64—65 and 69—71, which are provided to operate the ignition circuit (not shown). This invention is not directed to this detail, which is 30 the subject of other copending and issued patents.

The feature of this invention is the application of friction as the sole initial controlling means to counteract the centrifugal force of the governor.

Operation

35

In the operation of the governor, the friction imposed by the resiliency of the distribution member 47 and the friction pad 36 tends to retard the advance of the ignition cam timer 43 and to oppose the effect of the centrifugal force exerted by the weights 27 and 28. When the centrifugal force overcomes the friction, the plate 23 moves a distance determined by the slot 21, and the pin 15 is then engaged by the plate 23 and the spring 45 becomes operative to resist the advance of the ignition cam 43.

It thus happens that the number of revolutions per minute at which the timing increases initially is determined by the friction of the distributor and of the pad 36. The subsequent advance of the ignition is determined by the tension of the spring 16 and the corresponding spring 19. It will be seen that the movement of the weights 27 and 28 against the cam 33 which is fixed to the shaft 55

10 causes the plate 23 to rotate in two distinct stages and to carry with it the shaft 24, which, in its turn, advances the timing cam 43 in the two distinct stages, at first at a rapid rate, then at a 5 slower rate.

What I claim is:—

1. In an ignition timing governor, circuit breaker and distributor, a governor housing having a closed end, a driving shaft, a driven shaft 10 coaxial therewith, a plate fixed to said driving shaft, pins projecting from said plate, a loose plate mounted on said driven shaft, pins mounted on said loose plate, resilient means connecting said pins with the first mentioned pins, a third plate fixed to the driven shaft, and having a pair of pins projecting therefrom, a pair of centrifugal weights pivotedly mounted to rotate thereon and having cam faces projecting therefrom, openings 15 in the edge of said third plate through which the pins of said loose plate project so that the loose plate may rotate a limited number of degrees before engaging with the fixed plate, a cam rigidly connected with the driving shaft and engaging with the cam faces of said centrifugal weights, a 20 circuit breaker cam, circuit breaker mechanism mounted in said governor housing, a distributor arm mounted on said driven shaft, friction means associated with said distributor arm for the purpose described.
2. In an ignition timing governor, circuit breaker and distributor, a governor housing having a closed end, a driving shaft, a driven shaft 25 coaxial therewith, a plate fixed to said driving shaft, pins projecting from said plate, a loose plate mounted on said driven shaft, pins mounted on said loose plate, resilient means connecting said pins with the first mentioned pins, a third plate fixed to the driven shaft and having a pair of pins projecting therefrom, a pair of centrifugal 30 weights pivotedly mounted to rotate thereon and having cam faces projecting therefrom, openings in the edge of said third plate through which the pins of said loose plate project so that the loose plate may rotate a limited number of degrees before engaging with the fixed plate, a cam rigidly 35 connected with the driving shaft and engaging with the cam faces of said centrifugal weights, a circuit breaker cam, circuit breaker mechanism mounted in said governor housing, friction means 40 associated with said distributor arm for the purpose described.
3. In an ignition timing governor and distributor, a housing therefor having a closed end, a driving shaft, a driven shaft coaxial therewith, a plate fixed to said driving shaft, pins projecting from said plate, a loose plate mounted on said driven shaft, pins mounted on said plate, springs connecting said pins with the first mentioned pins, a plate fixed to the driven shaft, a pair of centrifugal weights pivotedly mounted to rotate thereon and having cam faces integral therewith, means permitting the loose plate to freely rotate 50 a limited number of degrees and then to engage with the fixed plate, a cam rigidly connected with the driving shaft and engaging with the cam faces of said centrifugal weights, a circuit breaker cam, a distributor arm mounted on said driven shaft, friction means associated with said distributor arm comprising an electrical conductor yieldably 55 mounted on said arm, a central conductor and a series of conductors mounted in a circle around said first conductor in the closed end of said housing.
4. In an ignition timing governor, a driving shaft, a plate rigidly mounted thereon, a second plate mounted for relative circumferential movement with reference to the first plate, a third plate mounted to turn freely through a limited angle on said shaft, a circuit breaker cam rigidly connected with the third plate, spring means connecting the first plate to the second plate, a governor for advancing the third plate, and a lost motion connection between the second and third plates 10 to relieve spring tension from the second plate when the third plate is only partially advanced.
5. In an ignition timing governor, a driving shaft, a plate rigidly mounted thereon, a cam rigidly connected to said plate, a second plate driven 15 by said shaft, a third plate having limited free circumferential movement on said shaft, a timing cam rigidly connected to the third plate, centrifugal members mounted on the third plate and engaging the first cam to cause relative advance 20 of the third plate as said members move outwardly, and spring means connecting the first and second plates to oppose the relative advance of the latter.
6. In an ignition timing governor, a driving 25 shaft, a plate rigidly mounted thereon, a second plate mounted for advance movement with relation to the first plate, a third plate mounted for limited advance movement with reference to the second plate, a circuit breaker cam rigidly connected to the third plate, centrifugal means for advancing the third plate, frictional means resisting the advance of the third plate, and spring means resisting the influence of the centrifugal 30 means upon the second plate.
7. In an ignition timing governor, a driving shaft, a plate rigidly mounted thereon, a second plate mounted for advance movement with relation to the first plate, a third plate mounted for limited advance movement with reference to the second plate, a circuit breaker cam rigidly connected to the third plate, centrifugal means for advancing the third plate, and spring means 35 operable to resist such advance only after a predetermined initial advance has been completed.
8. In an ignition timing governor, a driving shaft, a member mounted for advance movement with reference to said shaft, a plate mounted for advance movement with reference to said member, a circuit breaker cam rigidly connected to 40 said plate, centrifugal means for advancing said plate and cam, a pin and slot connection limiting the advance of said plate with reference to said member, and spring means resisting the advance of said member with reference to the 45 shaft.
9. In an ignition timing governor, a shaft, a circuit breaker cam mounted for relative advance movement with reference to the shaft, a governor for effecting the advance of said cam, frictional 50 means opposing the initial advance of the cam, and spring means opposing further advance thereof only after the initial advance has been completed.
10. In an ignition timing governor, a shaft, a circuit breaker cam mounted for relative advance movement with reference to the shaft, a governor for effecting the advance of said cam, and spring means operable to resist such advance only after a predetermined initial advance has 55 completed.

MARION MALLORY.
